FIG.5

Fig. 1 is a perspective view of a medical lamp head, showing the new design with portions of the patterned detail of the bottom of the light member omitted for convenience of illustration, it being understood that said pattern covers the entire bottom of the light member as shown in Fig. 2;

Fig. 2 is a bottom plan view thereof;

Fig. 3 is a side elevation thereof;

Fig. 4 is a view partly in front elevation and partly in vertical section through the medical lamp head; and

Fig. 5 is an enlarged top plan view thereof.

I claim:

The ornamental design for a medical lamp head, substantially as shown.
